Lempco Products, Inc., Bedford, Ohio, a cor-
poration of Ohio

Application November 4, 1939, Serial No. 302,906

20 Claims.

(Cl. 51—151)

This invention relates, generally, as indicated, to surfacing machines but relates more specifically to a machine for finishing or refinishing plane surfaces.

Heretofore considerable difficulty has been experienced in producing plane surfaces of large area particularly when such surface is part of a heavy and bulky article. This difficulty is acutely appreciated when attempting to produce a satisfactory finish on warped or marred gasket engaging surfaces of internal combustion motor blocks and heads. It is also appreciated in producing a satisfactory finish for clutch pressure plates.

Orthodox means for satisfactorily finishing plane surfaces are a grinding machine wherein a revolving abrasive wheel is utilized, a planer and a milling machine. Another means is moving the surface to be finished over a plane surface which supports abrasive material. The former requires accurate positioning of the surface to be finished with respect to the machine. The latter frequently results in ridges and high and low areas.

This invention has for its primary object the provision of a machine of the latter type wherein the abrasive moves intermittently.

Another object is to devise a machine of the character described which moves the abrasive and the surface to be finished in the same direction.

Still another object of the invention is to reduce packing or filling of the abrasive.

A further object is the provision of means to lock the abrasive while it is not in motion.

Further objects are to provide a device of the character described which is capable of operating rapidly, producing a satisfactory finish, economical to manufacture and jam proof.

To the accomplishment of the foregoing and related ends, said invention, then, consists of the means hereinafter described and particularly pointed out in the claims; the annexed drawings and the following description setting forth in detail certain mechanism embodying the invention, such disclosed means constituting, however, but one of various structural forms in which the principle of the invention may be used.

In said annexed drawings:

Fig. 1 is a plan view of a machine embodying this invention with portions thereof broken away in order to better show the plate;

Fig. 2 is a front elevation of the machine shown in Fig. 1;

Fig. 3 is a longitudinal cross-sectional view of the machine shown in Fig. 1;

Fig. 4 is a fragmentary view taken along the line 4—4 of Fig. 3;

Fig. 5 is a fragmentary view taken along the line 5—5 of Fig. 3;

Fig. 6 is a sectional view taken along the line 6—6 of Fig. 1;

Fig. 7 is a view showing the abrasive driving and locking mechanism which is part of this invention;

Fig. 8 is a front elevation of Fig. 7;

Fig. 9 is a view taken along the line 9—9 of Fig. 8; and

Fig. 10 is a detail front elevation of a gear and means for driving the same.

Referring to the drawings and more particularly to Figs. 2 to 5 thereof, there is provided a frame structure comprising legs 15, having inwardly extending ears 16, cross members 17 and bed 18.

Suitably supported as by welding to legs 15 is a plate 20 upon which is mounted a motor 21 which by means of a belt or chain within the guard 22 drives gears within the gear box 23 which is suspended from the ears 16 and which transmit power to shaft 24 upon which freely rotates a gear 25.

Extending below the bed 18 are cylindrical slideways 28 which are secured to the cross-members 17 by means of pins 29.

As is shown in Figs. 3, 4 and 5, a saddle 31 is slidably mounted on slideways 28 which extend through holes in horizontal bosses 32 of the saddle 31 which has secured to its bottom a rack 33 in mesh with gear 25.

Secured to vertical flanges 35 of saddle 31 on opposite sides of the bed 18 are upwardly extending standards 36 into each of which a rack 37 is incorporated.

Adapted to slide on each standard 36 is a member 40 in which is journalled cylindrical slideways 41 and 42. Housed within each member 40, in mesh with racks 37 and keyed to slideway 42, are pinions 43. The ends 44 of the slideway 42 are square or hex to provide means for simultaneously rotating both pinions to adjust the height of slideway 41 and 42 with respect to the bed 18.

A nut 45 on each end of slideway 41 insures proper positioning thereof with respect to members 40.

A resilient pad 47, such as rubber, is interposed between the bed and the plate 48, which may assume any form such as is described in copending application, Serial No. 279,890, one characteris-

tic of which is angularly extending slots 49, and another characteristic of which is a slight arch in its longitudinal section thereof.

Encircling the bed 18 and the plate 46 is an endless abrasive belt B which may take the form of a strong flexible backing, which may be metallic or fibrous, such as paper or cloth facing adhered thereto. To guide and drive the endless abrasive belt there is secured to the corners at one end of the plate 46 and projecting therefrom brackets 50 and at the other end brackets 51 in which are journalled two shafts 53 and 54 which carry large and small rollers 55 and 56 respectively. To adjust the tension in the belt B the brackets 51 have a slot 58 through which bolts 59 extend and engage the plate 48.

The mechanism to intermittently drive or shift the abrasive belt is within the guard 65 and, as seen in Figs. 7 and 8, comprises gear 66 and smaller gear 67 keyed respectively to the shafts 53 and 54, ratchet wheels 68 and 69 keyed respectively to shafts 53 and 54, a bell pawl 70 freely rotatable on the shaft 54 engaging the ratchet wheel 68 and pawl 71 freely rotatable on the shaft 53 engaging ratchet wheel 69. A third pawl 72 freely rotates about the stud 73 projecting from the lower end 74 of the pawl 70. A spring 75 which engages pins 76 and 77 projecting respectively from pawls 71 and 72 normally maintains them in engagement with their respective ratchet wheels. Extending through a slot in the ear 80 which projects from bed 18 is a member 81 which is pivotally attached to a bolt 82 at the end 74 of the pawl 70. To normally maintain the pawl 70 in engagement with ratchet wheel 68 there is surrounding the member 81 a coil spring 83, one end of which abuts against the ear 80 and the other end of which abuts against the washer 84 which is backed by pin 85 of the member 81 which may be provided.

Means to position and drive the article A to be surfaced in a device embodying this invention is mounted on slideways 41 and 42 and preferably comprises the structure shown in Fig. 1 and fully disclosed in co-pending application Serial No. 281,425.

Slidably mounted on slideways 41 and 42 is a carriage 90, on either side of which projects a stud (not shown), about one end of which rotates ratchet wheel 91 and about the other end of which rotates a T-shaped member 92, the horizontal arm of which is slotted as at 93 to receive bolts 94 which engage holes in the article A to be surfaced. The vertical arm of the T has a projection upwardly through the opening 89 of the carriage 90 and pivotally carries a pawl (not shown) which engages the ratchet wheel 91.

As is shown in Fig. 1, the bolts 94 are off-set with respect to the longitudinal axis of the article A so that if the saddle and consequently the article are driven along the abrasive belt B the article and the T member 92 will rotate about said stud projecting on either side of the carriage 90 as an axis causing the said pawl which is not shown to rotate said ratchet wheel 91. When the drive is reversed the article will swing in the opposite direction and return last said pawl to its original position. This swinging of the article is limited by said stud, which is not shown, bumping against the narrow neck 95 of the opening 89.

A pawl 96 normally in engagement with ratchet wheel 91 permits rotation thereof in only one direction.

Pivotally connected to bars 97, which by means

of a bolt 98 are anchored to slideways 41 and 42 and lock the same against rotation is an arm 99, the other end of which is pivotally connected at 100 to the ratchet wheel 91 so that as the latter rotates the carriage and consequently the article A is caused to move laterally with respect to the abrasive belt B. Secured to an upwardly extending boss of carriage 90, as by means of a bolt extending through a slot 102, is an arm 103 which 10 clears the ratchet wheel 91 and arm 99. One end of the arm 103 has a threaded hole which engages the bolt 104, the lower end of which is snugly encircled by one end of a coil spring, the other end of which engages the upper surface 15 of the article A to urge it against the belt B.

As was hereinbefore said, the gear 25 rotates freely about the shaft 24 and is in mesh with the rack 33 of the saddle 31 to provide a drive for the same. As is seen in Fig. 10, in order to 20 couple the shaft 24 with the gear 25 a bracket 105 is keyed to the former and is slotted to accommodate spring leaves 106 which are secured thereto by means of a bolt 107 which passes through an aperture in said leaves and engages 25 said bracket. Studs 108 project from gear 25 and are engageable by leaves 106. When the shaft 24 rotates counter-clockwise as viewed in Fig. 10, the spring leaves and studs assume the 30 full line relationship shown therein, and when the shaft 24 rotates in the opposite direction this relationship changes to that shown by the dotted lines therein. When the stud 108 and the spring 106 make contact, one end of the latter flexes as seen at 109 to absorb the contact shock 35 and prevent sudden change in direction of rotation of the gear 25.

To change the direction of rotation of the shaft 24 so that the carriage 31 and consequently the article A may be reciprocated, a clutch is provided within gear box 23 which when in one position drives the shaft 24 in one direction and when in a second position drives the shaft 24 in the opposite direction.

The clutch may take any well known form as 45 its exact features constitute no part of this invention. The clutch is operated or shifted from one position to the other or into neutral by means of the shaft 110 which is connected to a hand lever 111.

Pivotally attached to the top of the gear box 23 and retained thereon by a stud and nut 112 is a lever 113, one end of which extends through a slot 114 in the lever 111. The other end of the lever 113 has a downwardly extending finger 115. The gear 25 is provided with arcuate slots 120 through which extend bolts 121, one end 122 of which projects far enough from the gear 25 to engage the finger 115 as the gear 25 tends to be rotated thereby, shifting the lever 111 and reversing the direction of rotation of the gear 25. It is thus seen that the length of the stroke of the saddle 31 is determined by the size of the angle subtended by the arc between the bolts 121 and that the location of the stroke is determined by the location of the bolts 121. The dotted lines in Fig. 3 indicate the position to which the saddle 31 moves at the end of each stroke.

Fig. 9 shows an optional or supplemental coil 70 spring 125 encircling the stud 73 and adapted to maintain the pawl 72 in engagement with the ratchet wheel 69.

Assuming the parts as shown in Figs. 1 and 2, in operation the following functions are carried out:

The switch 126 starts the motor 21 which rotates the gear 25 in mesh with the rack 33, which moves the saddle 31, standards 36, slideways 41 and 42, carriage 90 and consequently the article A in a longitudinal direction causing the article A to swing laterally. Before the end of the stroke to the left of Figs. 1 and 2 the flange 35 engages the rubber tip 86 of the member 81 and pushes it to the left through the slot in the ear 80 to rotate the pawl 70 about the shaft 54 causing the pawl 70 to disengage the ratchet wheel 68 shortly before the pawl 72 contacts its respective tooth of the ratchet wheel 69 to drive the same and causing the shaft 54, gear 67 and the roller 56 to rotate and the belt B to shift. The gear 67 drives the gear 66, the shaft 53, roller 55 and the ratchet wheel 68. The swinging of the article A is limited by the neck 95 and the longitudinal movement is limited by the contact of one bolt 121 with the finger 115 to disengage the clutch and then by inertia to throw it into reverse position. Upon reversing the direction of the shaft 24, the spring leaves 105 flex as they contact a different stud 108 and cushion the reversal of direction of the gear 25 causing the article A to move back to its original position and simultaneously swinging the article A to give it lateral motion. The lateral motion changes direction every 180° of rotation of the ratchet wheel 91.

When such reversing in the longitudinal motion of the article A takes place, the member 81 and pawl 70 and 72 assume their normal position as shown in Figs. 7 and 8 due to the influence of the spring 83.

As is shown in Fig. 8, the abrasive face of the belt B contacts the roller 56 while the back of the belt B contacts the roller 55. This combined with the tension adjustment of the brackets 51, the difference in the number of teeth in the gears 66 and 67 and the fact that both rollers 55 and 56 are driven, provides a positive drive for the belt B. The three pawls 70, 71 and 72, plus the gears 66 and 67, lock the belt against the driving force created by movement of the article A. The disengagement of the pawl 70 before the engagement of the pawl 72 prevents jamming and renders the device fool-proof.

Ripping, destruction or wearing out of the belt is retarded by moving it only simultaneously with and in the same direction as article A. By moving the belt different portions thereof are presented to the article A resulting in less packing of the abrasive of the belt B and a better finish on the surface of the article A which is in contact therewith. This packing is further lessened because as the belt travels over the rollers the metallic particles removed from article A and particles of abrasive which might become loosened from the belt B drop off. To insure against such packing of "foreign" matter, a stiff wire brush or scraper 130 in contact with the abrasive belt B may be provided and is preferably mounted on the rack 33 below the bed 18 for freeing such matter.

The cushioning effect of spring leaves prevents jars which are injurious to the finish of the surface and to the machine.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a surfacing machine, an endless abrasive bearing belt and means for intermittently locking said belt, said means comprising a pair of ratchet wheels the teeth of one being oppositely disposed relative to the teeth of the other, and a pair of pawls one in engagement with each of said ratchet wheels.
2. In a surfacing machine, an endless abrasive bearing belt and means to alternately lock and move said belt, said means comprising a pair of oppositely disposed ratchet wheels, a pair of pawls one in engagement with each of said ratchet wheels, a third pawl engaging one of said ratchet wheels and means for actuating said third pawl and releasing one pawl of said pair of pawls.
3. In a surfacing machine, an endless abrasive bearing belt and means for alternately locking and moving said belt, said means comprising a pair of oppositely disposed ratchet wheels, a pair of pawls one in engagement with each of said wheels, and a third pawl pivotally carried by one of said pair of pawls and in engagement with one of said pair of ratchet wheels.
4. In a surfacing machine, an endless abrasive bearing belt, a pair of shafts, a pair of rollers one carried by each of said shafts, each of said 30 rollers being in engagement with said belt, driving means connecting said shafts, a pair of ratchet wheels one carried by each of said shafts, and a pair of pawls each in engagement with one of said ratchet wheels.
5. In a surfacing machine, an endless abrasive bearing belt and means for intermittently locking said belt, said means comprising a pair of shafts, driving means connecting said shafts, a pair of oppositely disposed ratchet wheels one on each of said shafts and a pair of pawls each in engagement with one of said ratchet wheels.
6. In a device of the character described, a source of power, a shaft driven by said source, means interposed between said shaft and said 45 source for reversing the direction of rotation of said shaft, a member secured to said shaft, a member in alignment with said shaft, a pin carried by one of said members and a spring carried by the other of said members, said spring being adapted to engage said pin, a second pin carried by one of said members adapted to engage said means to operate the same.
7. In a surfacing machine, an abrasive bearing belt, a pair of standards reciprocable relatively to said belt one on each side of said belt, each of said standards having a rack thereon, a pinion in engagement with each of said racks, means connecting said pinions slidable on said standards whereby said pinions may be simultaneously rotated, said means being adapted for maintaining an article in engagement with said belt, and means for reciprocating said standards.
8. In a device of the character described, an abrasive bearing fibrous strip, means for moving an article to be surfaced along said strip and a brush carried by said means in engagement with said strip.
9. In a surfacing machine, an endless abrasive bearing strip, a pair of shafts, driving means interconnecting said shafts, a pair of rollers each on one of said shafts and in engagement with said belt, a ratchet wheel on one of said shafts, an oppositely disposed ratchet wheel on the other of said shafts, a pawl pivotally mounted on one of said shafts and in engagement with one of

said ratchet wheels, a pawl pivotally mounted about the other of said shafts and in engagement with the other of said ratchet wheels, a third pawl adapted for driving one of said ratchet wheels, and means whereby actuation of said third pawl disengages one of said first-named pawls.

10. In a surfacing machine, the combination of a plate, an abrasive bearing belt on said plate, and a reciprocating brush in contact with said belt.

11. The combination of a plate, an endless abrasive belt encircling said plate, means for reciprocating an article relative to said strip, a brush carried by said means in contact with said strip on that side of said plate which is opposite from said article.

12. In a device of the character described, an abrasive bearing strip, means for reciprocating an article along said strip, means responsive solely to the end portion of a reciprocating stroke of said article for moving said abrasive strip in the same direction as said article is travelling, and means for positively locking said abrasive strip while said responsive means is inactive.

13. In a device of the character described, the combination of a stationary plate, an abrasive bearing strip on one side of said plate, a slideway on the other side of said plate and means engaging said slideway for reciprocating an article on said abrasive strip.

14. In a surfacing machine, an endless abrasive bearing belt and means for intermittently locking said belt, said means comprising a pair of ratchet wheels, the teeth of one being oppositely disposed relative to the teeth of the other and a pair of pawls one in engagement with each of said ratchet wheels, and means for actuating one of said pawls.

15. The combination of a plate, a belt on said plate, means for moving said belt, means for moving an article in contact with said belt whereby work is performed, a shaft for driving said last-named means, reversing means interposed between said shaft and said last-named means, and an element actuated by said shaft for controlling said reversing means.

16. The combination of a plate, a belt on said

plate, movable means for supporting an article in contact with said belt whereby work is performed, means for driving said means in one direction and then in another direction, and 5 control means responsive to the amount of movement of said first-named means for controlling the direction in which said last-named means drives said first-named means.

17. In a device of the character described, the combination of a plate one side of which is a plane surface, an abrasive bearing strip resting on said surface whereby an area of said strip lies in a plane parallel to said plane surface, a slideway on the other side of said plate, and 10 means slidable on said slideway and projecting above said area for moving an article in contact with said area.

18. In a device of the character described, the combination of a plate, an endless abrasive bearing strip encircling said plate and resting on one side thereof, a slideway on the other side of said plate, and means slidable along said 15 slideway and projecting beyond said first-named side for reciprocating an article in contact with that portion of said abrasive belt which is supported by said first-named side.

19. The combination of a plate, an abrasive belt on said plate, means for moving said belt along said plate, means movable along said plate 20 for moving an article in contact with said belt whereby work is performed, a source of power, a member interconnecting said source and said last-named means for moving the latter, reversing means interposed between said member and said last-named means, and an element actuated by said member for controlling said reversing means.

20. The combination of a plate, a belt on said plate, means movable along said plate for moving an article in contact with said belt whereby 25 work is performed, a source of power, a member interposed between said source and said means for moving the latter, reversing means interposed between said member and said first-named means, and an element actuated by said member for controlling said reversing means.

JOHN Y. BLAZEK.
